215,610

GOLF PUTTER HEAD

David Galambossy, 4259 Maureen Drive,
Austintown, Ohio 44515

Filed Jan. 27, 1969, Ser. No. 15,521

Term of patent 14 years

Int. Cl. D21—03

U.S. Cl. D34—5

FIG. 2

FIG. 1

FIG. 3

FIG. 5

FIG. 4

FIG. 6

The dotted line showing of a fragmentary portion of a club shank in FIGURES 1, 2, 4, and 5 is for illustrative purposes only.

I claim:

The ornamental design for a golf putter head, substantially as shown and described.
